UNITED STATES PATENT OFFICE.

SAMUEL ALFRED HAINES, OF GARRETT, TEXAS.

WRENCH.

SPECIFICATION forming part of Letters Patent No. 609,670, dated August 23, 1898.

Application filed February 7, 1898. Serial No. 669,411. (No model.)

To all whom it may concern:

Be it known that I, SAMUEL ALFRED HAINES, a citizen of the United States, and a resident of Garrett, in the county of Ellis and State of Texas, have invented certain new and useful Improvements in Wrenches; and I do hereby declare that the following is a full, clear, and exact description of the invention, which will enable others skilled in the art to which it applies to make and use the same, reference being had to the accompanying drawings, which form a part of this specification.

My invention relates to wrenches for removing the nuts from vehicle-axles; and its object is to provide an improved construction of the same having means for engaging with the rim of a wheel-hub whereby the nut is removed or screwed on by turning the wheel.

My invention consists, essentially, in the combination, with an ordinary wrench, of an adjustable head having a slot which engages with the shank of the wrench and formed with a socket adapted to engage with the rim of the wheel-hub and provided with a set-screw for holding it in place, as hereinafter fully described and claimed.

In the accompanying drawings, Figure 1 is an elevation of an ordinary wrench provided with my improvements. Fig. 2 is a vertical cross-section of the same. Fig. 3 is a perspective view of the head which engages with the wheel-hub rim removed.

In the said drawings, the reference-numeral 1 designates a wrench for removing the nuts from vehicle-handles which may be of any ordinary or suitable construction.

The numeral 2 designates my improved attachment or head, consisting of a metal block formed with a rectangular opening 3 and an intersecting slot 4 at one end, with which opening is adapted to engage the shank of the wrench. At the opposite end said head is formed with two outwardly-extending arms 5 and 6, one of which is formed with a screw-threaded opening for the passage of a set-screw 7.

The numeral 8 designates a short screw-threaded bolt having a head 9 and a nut 10. This bolt is inserted in the slot 4, with its head resting against the shank of the wrench, and the nut 10 is then screwed on the outer end thereof, thereby securely holding the head to the shank.

In practice one edge of the wrench-shank

is passed through the slot 4 at the end or 55 head of the block 2 and is then turned so that the flat sides of the shank will engage with the upper and lower walls of the opening 3. To remove the nut, the rectangular jaw of the wrench is engaged with the nut and the arms 60 5 and 6 engaged with the rim of the wheel-hub and held securely thereto by the set-screw 7. By now turning the wheel backward the nut will be unscrewed. A reverse movement will screw the nut home. By this 65 means a great leverage is obtained, so that the nuts may be readily screwed up and unscrewed. The head or block 2 is adjustable on the shank, which loosely passes therethrough, so that it can be moved to and from 70 the jaw, so as to adapt the device to hubs of varying sizes.

For the purpose of preventing injury to the wheel-hub by the set-screw 7 I provide the block with a recess 8', in which is seated one 75 end of a spring-plate 9'. The set-screw in this instance does not come in contact with the wheel-hub, but presses the plate against the same. By this means while the head is securely held to the hub marring or otherwise 80 injuring the latter is prevented.

In some cases I may make the head or block integral with the shank of the wrench; but I prefer the construction first described, as the head can be adjusted to suit varying sizes of 85 hubs.

Having thus fully described my invention, what I claim is—

1. As an improved article, an attachment for wrenches consisting of the head formed 90 with an opening in one end and an intersecting slot, the arms at the opposite end and the set-screw, substantially as described.

2. The combination with a wrench, of the head formed with an opening and an intersecting slot at one end and the headed bolt 95 engaging with said slot, its nut, the arms at the opposite end of said head, the set-screw passing through one of said arms, and the spring-plate located between said arms, substantially as described.

In testimony that I claim the foregoing as my own I have hereunto affixed my signature in presence of two witnesses.

SAMUEL ALFRED HAINES.
